(57) **CLAIM**

The ornamental design for a folding workstation backpack, as shown and described.

DESCRIPTION

A portion of the disclosure of this patent document contains material which is subject to copyright protection. This patent document may show and/or describe matter which is or may become trade dress of Ofyce. The copyright and trade dress Ofyce has no objection to the facsimile reproduction by anyone of the patent disclosure as it appears in the Patent and Trademark Office patent files or record, but otherwise reserves all copyright and trade dress rights whatsoever.

FIG. 1 is a top right rear perspective view of a folding workstation backpack in the backpack configuration showing my new design;

FIG. 2 is a bottom left front perspective view thereof;

FIG. 3 is a front view thereof;

FIG. 4 is a rear view thereof;

FIG. 5 is a top view thereof;

FIG. 6 is a bottom view thereof;

FIG. 7 is a right view thereof;

FIG. 8 is a left view thereof;

FIG. 9 is a top front perspective view in the workstation configuration thereof; and,

FIG. 10 is a bottom rear perspective view in the workstation configuration.

1 Claim, 10 Drawing Sheets
